Des. 240,234
Patented June 8, 1976

240,234

COMBINED TELEPHONE AND ELECTRICAL OUTLET RECEPTACLE

Edward Denman Bunnell, Palm Harbor, Fla., assignor
to AMP Inc., Harrisburg, Pa.

Filed Jan. 31, 1975, Ser. No. 546,048

Term of patent 14 years

Int. Cl. D13—03

U.S. Cl. D26—1 B

119 2

FIG. 1 is a perspective view of a combined telephone and electrical outlet receptacle showing my new design.

FIG. 2 is a right side elevational view thereof.

FIG. 3 is a left side elevational view thereof.

FIG. 4 is a front elevational view thereof.

FIG. 5 is a top plan view thereof.

I claim:

The ornamental design for a combined telephone and electrical outlet receptacle, as shown.
